UNITED STATES PATENT OFFICE.

THOMAS C. BOOTH, OF NEW ROCHELLE, NEW YORK, ASSIGNOR TO THE CONSOLIDATED
FRUIT JAR COMPANY, OF NEW YORK, N. Y., A CORPORATION OF NEW YORK.

COMPRESSIBLE TUBE.

972,095

Specification of Letters Patent.

Patented Oct. 4, 1910

Application filed April 2, 1909. Serial No. 487,553.

To all whom it may concern.:

Be it known that I, THOMAS C. BOOTH, a citizen of the United States, and residing at New Rochelle, in the county of Westchester, 5 State of New York, have made a certain new and useful Invention in Compressible Tubes, of which the following is a specification.

This invention relates to compressible tubes, and particularly to devices of this 10 nature adapted to contain paint, tooth paste, or other toilet preparations, vaseline compounds, inks and the like.

The object of the invention is to provide a tube of the character referred to, and for 15 the purpose stated, which presents a clean bright surface, and to the surface of which labels may be efficiently applied, and wherein the contents of such tube or container may be expelled when required for use by compressing such tube.

Other objects of the invention will appear more fully hereinafter.

The invention consists substantially in the 25 construction, combination, location and relative arrangement of parts, all as will be more fully hereinafter set forth, as shown in the accompanying drawing and finally pointed out in the appended claims.

In the accompanying drawing,—Figure 1 30 is a view in elevation of a compressible tube or container embodying the principles of my invention, a part being broken out. Fig. 2 is a broken detail view in section on the line 2, 2, Fig. 1. Fig. 3 is a view similar to Fig. 1 35 showing a modified form of tube embraced within the spirit and scope of my invention. Fig. 4 is a view similar to Fig. 2 showing another modified form of my invention.

It is a common expedient to employ compressible tubes or containers for paints, 40 toilet preparations, tooth paste, vaseline compounds, inks and similar liquid, fluid or plastic substances.

As ordinarily constructed the tubes heretofore employed for this purpose have been 45 formed of a suitable soft metal or foil, by pressing the same into tubular shape, reduced at one end to form a nipple upon which is received a cap to close the end of the tube. The other end of the metallic tube is 50 collapsed or folded to permanently close such end. The smooth polished metallic exterior surface of such tubes renders it difficult to efficiently apply adhesive printed la-

bels to such surface to indicate the nature or 55 character of the contents of such tubes. Moreover, if it be attempted to emboss the tubes with the name of the manufacturer or dealer, the address or other matter, the embossing fails to stand out with sufficient 60 clearness or boldness to be effective. Again, the smooth metallic surface of the tube rapidly becomes dulled thereby imparting a dingy soiled appearance which materially detracts from their salability. Where it has 65 been attempted to apply labels to such tubes it has been necessary to employ labels which are made to completely encircle the tube with the ends of the label overlapping and secured together, but, as above stated, this 70 does not efficiently secure the label to the tube and trouble and annoyance is experienced by reason of the labels slipping off the tubes.

It is among the special purposes of the 75 present invention to provide a compressible tube so constructed as to avoid the objections noted, wherein printed or other labels may be efficiently applied to the tubes and adhesively secured thereto, wherein the tubes 80 present a bright clean appearance and wherein names, letters or other matter embossed thereon will stand clearly and boldly.

In carrying out my invention I form the 85 tube A in the usual manner by pressing the same into tubular form by means of dies, or otherwise, and permanently close one end of such tube by collapsing or folding the tube material at such end upon itself, as indicated at B. At its other end the tube is 90 reduced to form a nipple C, adapted to receive a removable cap D, to close the same.

In accordance with my invention I propose to corrugate the body of the tube throughout its entire length in parallel lines. 95 These corrugations may be arranged to extend longitudinally of the tube and the entire length thereof, as indicated at E, Figs. 1 and 2, or they may be in the form of parallel rings encircling the body of the 100 tube, as shown at F, Fig. 3. If desired the corrugations may be formed only in the exterior surface of the tube as seen in Fig. 2, or they may be formed by suitably corrugating the entire transverse thickness of 105 tube material, as shown at G, in Fig. 4, in which event both the interior and the exterior surface of the tube is corrugated.

The corrugations may be formed by suitably pressing or rolling the tubes in properly shaped dies in a well known manner.

The corrugations, whether longitudinal or transverse, may be spaced apart as close or as far apart as may be desired, or in any desired relative degree or relation.

A compressible tube, corrugated as above described affords a surface to which an adhesive printed or other label may be efficiently applied without the necessity of the label completely encircling the tube and without the danger of slipping off. Moreover, the reflection of the light from the corrugated surface imparts a bright clean appearance which is a desirable feature in the marketing of the tubes containing the liquid, fluid or other form of substance. Again, in embossing or stamping or otherwise placing the name and address of the manufacturer or dealer, or other matter on the corrugated surface of the tube the embossed or stamped or otherwise produced lettering by reason of such corrugations, stand out boldly, clearly and prominently.

In the case where the tubes are corrugated both on the interior and exterior surfaces thereof, as above noted, the tubes are somewhat stiffened and hence are enabled the

more readily to retain their cylindrical shape.

In order to expel the contents of the tube for use it is only necessary to remove the cap D, and to somewhat compress the body of the tube in the usual manner.

Having now set forth the object and nature of my invention and various constructions embodying the principles thereof, what I claim as new and useful and of my own invention, and desire to secure by Letters Patent is:

A compressible integral cylindrical tube or container having the material at one end thereof collapsed upon itself, whereby said tube is permanently closed at such end, said tube having a removable cap at the other end, the exterior surface of the body of such tube being corrugated or grooved in parallel lines, the interior surface of said tube being free from corrugations.

In testimony whereof I have hereunto set my hand in the presence of the subscribing witnesses, on this 29th day of March A. D. 1909.

THOMAS C. BOOTH.
